ARMING DEVICE FOR A MINE

Howard W. Semon, 4301 34th St., Brentwood, Md.
Filed Aug. 8, 1945, Ser. No. 609,693

4 Claims. (Cl. 102—16)

(Granted under Title 35, U.S. Code (1952), sec. 266)

This invention relates generally to arming devices for marine mines. More specifically, the invention relates to an arming device for a marine mine adapted to be launched from an aircraft in flight and to be planted in shallow water wherein the device maintains a detonator in a safe position with respect to a booster charge until the mine is immersed in water whereupon the detonator is moved into operative relation with respect to the booster charge and a pair of electrical contacts is closed.

It is an object of the present invention to provide an arming device for shallow water mines wherein new and improved means are employed for moving the detonator into operative relation with respect to the booster charge.

Another object is the provision of an arming device for shallow water mines in which the detonator is releasably held in a safe position until the mine is immersed in a body of water.

A further object is the provision of an arming device of the above character wherein a pair of electrical contacts is closed in time delayed relation with respect to the launching of the mine employing the arming device.

Additional objects and advantages of the present invention are those residing in and relating to the novel construction and arrangement of the elements thereof as will more clearly appear as the description proceeds, reference being made to the accompanying drawings of which:

Fig. 1 is a view in elevation of the device of the present invention according to the preferred embodiment thereof;

Fig. 2 is a vertical sectional view of the device shown in Fig. 1;

Fig. 3 is a view partially in section and partially in elevation taken along the line 3—3 of Fig. 1;

Fig. 4 is a view similar to that of Fig. 2 showing the device in the armed position;

Fig. 5 is a fragmentary sectional view similar to that of Fig. 3 and showing the contact assembly in the operated position;

Fig. 6 is a sectional view taken along the line 6—6 of Fig. 2; and

Fig. 7 is a sectional view taken along the line 7—7 of Fig. 1.

A detailed description of the structure and operation of the invention will now be given with reference to the accompanying drawings wherein like characters of reference refer to like parts throughout the several views. The numeral 10 indicates a cylindrical member having an axially disposed hexagonal bore 11 and a well 12, the well 12 being adapted to receive a booster charge 13 composed of a suitable explosive material such, for example, as tetryl, and comprising one element of an explosive train. A channel 14 is cut into the cylindrical member 10 extending through to the bore 11 with another channel 15 interconnecting the well 12 and channel 14. A hole 16 is cut through the cylindrical member 10 in such a manner that the axis thereof lies in the same horizontal plane as the axis of channel 14, a horizontal passageway 17 being arranged between the hole 16 and bore 11.

The cylindrical member 10 is provided with reduced end portions, the lower or inner end portion thereof being threaded to receive a cap 18 to seal off the booster charge 13 and the upper or outer end portion being threaded to receive an internally threaded annular member 19. A hexagonal plunger 21 passes through the mem-

2

ber 19 and is arranged in the bore 11, the plunger 21 being provided with a channel 22 the axis of which is arranged at right angles to the axis of hole 16. A suitable explosive primer 23 is arranged in the hole 16 with a screw 20 mounted therein for sealing purposes and comprises another element of the aforesaid explosive train, the explosive train further comprising a detonator 24 arranged in the channel 22 and tetryl leads 25 disposed in channels 14 and 15, another screw 30 being arranged in channel 14 for sealing off the tetryl leads contained therein.

The annular member 19 is provided with an internally threaded flanged portion 26 within which is disposed an inverted cup-shaped member 27 secured to the member 19 by means of a nut 28 which may be adjusted by means of a spanner wrench. A flexible gasket element 29 is arranged between the cup-shaped member 27 and the annular member 19 in order to provide a water tight connection therebetween. The plunger 21 is further provided with a reduced portion 31 threaded to receive a nut 32 and washer 33 whereby the gasket 29 may be tightened against a ring member 34 affixed to the plunger as by brazing and engaging the six points of the hexagonal portion thereof.

25 A substantially cup-shaped member 35 is crimped to the member 27 and carries therein a salt washer 36 sleeved about plunger 21 and adapted to be dissolved when immersed in water. The plunger 21 is provided with a reduced threaded extremity 37 adapted to receive a knurled nut 38, a coil spring 39 being disposed about the plunger 21 and having the upper end thereof in engagement with the crimped portion of member 35 and the lower end thereof in engagement with the nut 32. By tightening nut 38, the plunger and detonator 24 are caused to move outwardly to a retracted position, Fig. 2, whereby spring 39 is compressed and the detonator displaced from the explosive train, the washer being arranged to releasably maintain the plunger and detonator in the retracted position.

35 The member 35 is provided with holes 42 through which extends an arming wire 43 adapted to pass through one side of the groove 44 cut into the periphery of the plunger thereby to releasably lock the plunger 21 in the retracted position. A ring 45 extends through a hole drilled into 40 the threaded extremity 37 of the plunger thereby preventing the nut 38 from being displaced as a result of shocks received thereby.

A contact assembly is secured to the cylindrical member 10 by the screws 46 and comprises a movable leaf spring contact 47 and a stationary contact element 48 each being insulated from the other and from the screws 46 by suitable strips of insulating material 49. The stationary contact element 48 is provided with a hole through which extends a cylindrical member 51 composed of any suitable insulating material such, for example, as Bakelite and having one end thereof affixed to the movable contact element 47. The other end of the member 51 extends into a channel 52 cut into the cylindrical member 10 and engages a plug 53 disposed within the channel 52, the plug 53 being normally in engagement with the plunger 21 by reason of the pre-loading effect produced by the movable contact 47. The plunger 21 is further provided with a recessed portion 54 adapted to be engaged by the plug 53 when the detonator 24 has been moved into operative relation with respect to the primer 23, thereby to cause the movable contact 47 to move into engagement with the stationary contact 48.

45 As heretofore described, the arming device of the present invention is especially adapted for use in connection with shallow water mines launched from an aircraft in flight. In operation, the arming wire 43 is rigidly se-

cured to the aircraft in any well known manner such that a mine employing the instant device and launched from the aircraft will cause the arming wire 43 to be pulled out of the groove 44, thereby releasing the plunger 21 for downward movement. As the mine strikes the water and becomes submerged therein, water seeps in around the knurled nut 38 and reacts on the salt washer 36 causing the washer to be dissolved in a predetermined interval in accordance with the composition of the washer. As the washer 36 is gradually dissolved, the plunger 21 is caused to move downward under pressure exerted thereon by the tension in the coil spring 39 such that when the washer is completely dissolved the plunger will have been extended to a position wherein the axis of the detonator 24 is in alignment with the axis of channel 14, Fig. 4, further downward motion of the plunger being prevented by reason of the engagement of the nut 38 with the recessed portion of the member 35. When this occurs the aforesaid explosive train is completed and contact 47 moves into engagement with contact 48, Fig. 5.

It will be noted that the primer 23 is adapted to be operated electrically by current passing through the leads 55, the leads 55 comprising the firing control system of the mine. When the primer is operated by current passing therethrough, a flame is generated thereby which explodes the detonator 24, the explosive train being thereafter completed to the booster charge 13 through the tetryl leads 25 in a well known manner. It will be further understood, that contacts 47 and 48 may be included in the circuit comprising the primer 23 or may be used to initiate the operation of a suitable arming clock well known in the art to which the invention appertains.

Briefly stated in summary, the present invention contemplates the provision of an arming device wherein a normally broken explosive train is completed by the inward or downward motion of a spring loaded plunger, the motion of the plunger being initiated after an arming wire has been withdrawn and a soluble washer dissolved.

While the invention has been disclosed in particularity with reference to an example thereof which gives satisfactory results, it readily will be understood by those skilled in the art, after understanding the invention, that further embodiments, modifications, and changes may be made without departing from the spirit and scope of the invention as defined by the claims appended hereto.

The present invention may be manufactured and used by or for the Government of the United States of America for governmental purposes without payment of any royalties thereon or therefor.

What is claimed as new and desired to be secured by Letters Patent of the United States is:

1. In an arming device, a housing means having an inner end and an outer end and aligned holes in the outer end, a channel in the inner end and an incomplete powder train contained in the inner end; a plunger slideably mounted within said housing for translatory movement from a retracted position to an extended position, said plunger having an outer end section, an inner end section, a circular peripheral groove on the outer end section, a recessed portion on the inner end section, and an explosive element contained in the inner end section and arranged therein for alignment with the powder train when the plunger is in the extended position; means for releasably retaining said plunger in said retracted position comprising an arming wire positioned in said aligned holes and said peripheral groove; means for perfectly aligning said groove with said holes to insure snag-free removal of said arming wire comprising plunger adjustment means adapted upon adjustment to move the plunger slightly when the plunger is in retracted position; means for moving said plunger inwardly to said extended position; a spring-biased plug disposed within said channel and adapted to spring into engagement with the plunger

5 recessed portion when the plunger is moved to extended position; and fire control electrical contact means connected to and closed by the plug when the plug springs into engagement with the plunger recessed portion.

2. In an arming device for a marine mine, the combination of housing means having an inner section, a channel, and an incomplete explosive train in the inner end section thereof, a plunger having a recessed portion and a completing explosive train element slideably mounted within said housing for translatory movement from a retracted position to an extended position, means for releasably retaining said plunger in retracted position, means for moving said plunger inwardly to extended position, a spring-biased plug slideably disposed within said channel and adapted to spring into secure engagement with the recessed portion of the plunger when the plunger is moved sufficiently inwardly to register the completing explosive element with the incomplete explosive train, and fire control switch means connected to and operated by said plug and adapted to be closed when said plug is sprung into engagement with the plunger recessed portion.

3. In an arming device, a housing means having an inner end, an outer end, aligned holes in the outer end, and a channel in the inner end; a movable plunger having an inner end section, an outer end section, a peripheral groove on the outer end section, and a recessed portion on the inner end section disposed within said housing; adjustment means for slightly moving said plunger inwardly and outwardly upon adjustment thereof to perfectly align said groove with said holes; a removable arming wire disposed in said groove and said holes to secure said plunger in a retracted position; means for moving said plunger inwardly from said retracted position to an extended position; a spring-biased plug disposed within said channel; and fire control electrical contact means controlled by said plug; said plug being adapted to close said electrical contact means and to move inwardly into engagement with said recessed portion when said plunger is moved to said extended position.

4. In an arming device for a marine mine, a housing having an inner end and an outer end and containing an incomplete explosive train at the inner end thereof and having two aligned holes at the outer end; a plunger slideably mounted within said housing for translatory movement from a retracted position to an extended position; said plunger having an inner end section, an outer end section having a threaded portion, a circular peripheral groove on the outer end section, and an explosive element contained in the inner end section and arranged thereon for alignment with said train to form a complete explosive train when the plunger is in said extended position; means for moving said plunger inwardly to said extended position; and means for retaining the plunger in an outward retracted position comprising an arming wire releasably positioned in said holes and said groove, a soluble washer disposed on the plunger inwardly of the threaded portion and resting on said housing, an adjusting nut screwed onto the threaded portion and abutting the soluble washer for slightly moving said plunger inwardly and outwardly to perfectly align said groove with said holes to insure snag-free removal of said arming wire.
